UNITED STATES PATENT OFFICE.

JOHN M. MASSEY, OF GAHANNA, OHIO.

ADJUSTABLE FIREPLACE-GRATE.

1,008,170.

Specification of Letters Patent.

Patented Nov. 7, 1911.

Application filed November 30, 1908. Serial No. 465,349.

To all whom it may concern:

Be it known that I, JOHN M. MASSEY, a citizen of the United States, residing at Gahanna, county of Franklin, and State of Ohio, have invented a certain new and useful Improvement in Adjustable Fireplace-Grates, of which the following is a specification.

My invention relates to a new and useful improvement in adjustable fireplace grates, and has for its object to provide an exceedingly simple and effective device of this character whereby the grate basket and fire-board and the front plates may be adjusted 15 to different sizes to fit different size fireplace openings.

With these ends in view, this invention consists in the details of construction and combination of elements hereinafter set 20 forth and then specifically designated by the claims.

In order that those skilled in the art to which this invention appertains may understand how to make and use the same, I will 25 describe its construction in detail, referring by letter to the accompanying drawing forming a part of this specification, in which—

Figure 1 is a front elevation of the fire-board showing the front plates in position. Fig. 2, a rear view of the adjustable lower front plate. Fig. 3, a front elevation of one of the sections of the lower front plate. Fig. 4, an end view thereof. Fig. 5, a rear view 35 of the fire-board showing the grate in position and the front plates removed. Fig. 6, a section at the line X—X of Fig. 5 showing the front plate and fender in position. Fig. 7, an edge view of the upper front plate. Fig. 8, a rear view thereof. Fig. 9, a front 40 elevation of the device, a portion of the upper front plate being removed to more fully show the under connecting plate. Fig. 10, a bottom view of the grate basket showing it partly extended, and Fig. 11, an edge 45 view thereof. Fig. 12, a front elevation of the grate, a portion thereof being broken away. Fig. 13, is a perspective view of one of the grate basket sections.

In carrying out my invention as here embodied, A represents the fire-board which is 50 formed of the two pieces B and C from metal or other suitable material which may be pressed to represent bricks, tiling or other artistic figures. In the upper ends of these 55 parts B and C are formed the slots D, and

on the backs of these parts are secured the hooks E which are adapted to engage with staples or screw eyes placed inside the chimney for holding the fire-board in position about the fireplace opening. 60

F represents a facing plate through which passes the screws or bolts G, one end of said screws passing through the slots D in the upper ends of the fire-board on which are placed the washers H and the nuts I. 65 It will be seen that by loosening the nuts I the two parts of the fire-board may be moved away from one another within the limit of the slots D thus allowing said fire-board to be made larger or smaller. 70

Formed with or secured to the inner edge of the fire-board are the supporting lugs J and K whereby the grate basket L may be held in position in the fireplace opening, said grate basket being formed of the sections M and N which are bent to form a front and bottom at right angles to one another, and in these sections are formed a number of slots O. 75

P is a face plate having a number of radiating arms Q through which pass the screws R, said screws passing through a number of the slots O then through the radiating arms S of the back plate T having threaded on their ends the nuts U whereby 85 they will be held in place. By loosening these nuts the sections M and N of the grate basket may be moved toward or away from one another, thus making the grate basket 90 narrower or wider so that it will fit the fire-board.

V is a top plate through which pass the screws W, the ends of said screws passing through the slots O formed in the bottom portion of the grate basket, and on the 95 ends of these screws are threaded the nuts Y whereby the screws may be held in place and the different parts of the grate basket held together. The top plate V forms a portion of the bottom of the grate basket 100 when the sections M and N are moved away from one another.

Formed from one side of the sections M and N in proximity to their upper ends are the rearwardly extending hooks Z which engage with the supporting lugs J. 105

In the bottom portion of the sections M and N are formed the notches A' by bending the metal downward or forming lugs there-with as indicated by B'. Through these 110

notches pass the supporting lugs K so that when the grate is in position it will be resting upon the lugs K, and the bent down portion or lugs B' will be on both sides of the supporting lugs K so that the grate will always be held in the same position.

C' is the lower front plate or guard which is composed of the sections D' and E', each of said sections being composed of 10 a face plate F' having a number of slots G' and air holes H' formed therein. To these face plates are secured the end pieces I' the tops of which are formed on an angle as indicated by J'. On this portion of the end 15 pieces is secured the top K' which with the upper edge of the face plate F' is beveled as indicated at L'. These sections are adjustably secured together by the facing plate M' by means of the screws N' which pass 20 through said face plate then through the slots G' in the sections D' and E', said screws having nuts O' threaded on their inner ends.

The facing plate M' has a number of air 25 holes P' formed therein which allows the air to pass through it forming a draft for the fire. If found desirable a number of the screws may have knobs Q' placed thereon before they are placed through the different 30 sections whereby the grate may be picked up or moved from place to place. The upper edge of the face plate M' forms with the face plate F' of the sections D' and E' a groove R' in which rests the lower edge 35 of a portion of the upper front plate S', said upper front plate being formed of the sections T' and U' having the slots V' formed therein.

A² is the lower joiner through which pass 40 the screws B², said screws then passing through the slots V' in the sections T' and U'. On the inner ends of these screws are threaded the nuts C² for drawing the sections T' and U' and the lower joiner A² 45 together and for holding the screws B² in place.

D² is the upper joiner through which pass the screws B², said screws passing through the upper slots V' and having threaded on 50 their inner ends the nuts C². Over these joiners is placed the blind E² to which is fastened a knob F² for lifting or moving the upper front plate from place to place.

G² denotes pins placed on the inside edge 55 of the fire-board sections B and C over which is placed the fender or guard C', the pins G² are in such a position that in placing the fender in position it must be raised up a certain distance or until the inner edge 60 of the top K' is above said pin, then by letting the fender down until the top rests on the pins G² said pins will cause the fender to move inward until the face plates F' of the sections D and E rest against the fire-board A. The pins H² are also secured to

the inside edge of the fire-board in proximity to the inner upper edge thereof so that the upper front plate when in position will rest against these pins so that they will be between these pins and the upper portion 70 of the fire-board, the lower edge of the upper front plate resting in the groove R' formed in the guard or fender C'.

In practice the fire-board A is set in front of the fireplace opening and the sections B and C moved toward or away from one another until the correct adjustment has been obtained when the screws and nuts are tightened holding the parts stationary in the adjustment obtained. The grate basket 75 is then adjusted until the hooks Z engage with the lugs J at which time the screws and nuts thereon are tightened so that the parts of the grate basket may be held securely together. Next the sections D' and E' of the fender or guard C' are moved toward or away from one another until its adjustment is secured. The face plate M' covering the space left between the ends of 80 these two sections, the air holes in these sections and the front plate will allow air to pass through the fender or guard forming a draft for the fire. The top plate of the fender or guard slanting downward and inward compels any of the fire or cinders 85 which may be dropped from the grate to fall inward underneath the grate. The upper front plate is next adjusted to fit the fire-board by moving the sections T' and U' toward or away from one another, the 90 joiners A² and D² and the blind E² covering up the space left between the sections 95 T' and U'.

From the foregoing description it will be 105 seen that but one set of patterns will be needed to produce a fireplace grate which will fit a number of fireplace openings of different sizes.

Of course I do not wish to be limited to the exact details of construction here shown 110 as these may be varied within certain limits without departing from the spirit of my invention.

Having thus fully described my invention, what I claim as new and useful, is—

1. In an adjustable fireplace grate, a fire-board composed of two sections having slots formed in their upper ends, a facing plate, screws passing through said facing plate and the slots formed in the upper ends of 120 the fire-board sections for adjustably securing said sections together, nuts threaded on the inner ends of said screws, supporting lugs formed with the inner edge of the fire-board, pins placed on the inner edge of the 125 fire-board, an adjustable grate basket attached to the supporting lugs, an adjustable fender or guard composed of two sections, and a facing plate having air openings therein, each section formed of a face plate hav- 130

- ing slots and air holes formed therein, side pieces, the upper ends of which are formed on an angle, secured to the backs of the face plates and a top secured to the upper ends 5 of the side pieces, the upper edge of the tops and the face plates forming a beveled joint, screws passing through the facing plate and the slots formed in the face plates of the sections for adjustably securing the face 10 plate and sections together, and nuts threaded on the inner ends of said screws for holding said screws in place, the tops of the sections adapted to rest upon the lower pins which are placed on the inner edge of the fire- 15 board for holding the guard or fender in position, as and for the purpose set forth.
2. In an adjustable fireplace grate, a fire-board composed of two sections having slots formed in their upper ends, a facing plate, 20 screws passing through said facing plate and the slots formed in the upper ends of the fire-board sections for adjustably securing said sections together, nuts threaded on the inner ends of said screws, supporting lugs 25 formed with the inner edges of the fire-board, pins placed on the inner edge of the fire-board, an adjustable grate basket attached to the supporting lugs, an adjustable fender or guard composed of two sections 30 and a facing plate having air openings therein, each section formed of a face plate having slots and air holes formed therein, side pieces, the upper ends of which are formed on an angle, secured to the backs of the face 35 plates and a top secured to the upper ends of the side pieces, the upper edge of the tops and the face plates forming a beveled joint, screws passing through the facing plate and the slots formed in the face plates of the 40 sections for adjustably securing the facing plate and sections together, nuts threaded on the inner ends of said screws for holding said screws in place, the tops of the sections adapted to rest upon the lower pins which are placed on the inner edge of the fire- 45 board for holding the guard or fender in position, a front plate composed of a number of sections adjustably secured together, and means for attaching said front plate be- tween the inner edges of the fire-board, as 50 specified.
3. In an adjustable fireplace grate, a fire-board composed of two sections having slots formed in their upper ends, a facing plate, screws passing through said facing plate and 55 the slots formed in the upper ends of the fire-board sections for adjustably securing said sections together, nuts threaded on the inner ends of said screws, supporting lugs formed with the inner edge of the fire-board, 60 pins placed on the inner edge of the fire-board, an adjustable grate basket attached to the supporting lugs, an adjustable fender or guard composed of two sections and a facing plate having air openings therein, 65 each section formed of a face plate having slots and air holes formed therein, side pieces, the upper ends of which are formed on an angle, secured to the backs of the face plates and a top secured to the upper ends 70 of the side pieces, the upper edge of the tops and the face plates forming a beveled joint, screws passing through the facing plate and the slots formed in the face plates of the sections for adjustably securing the facing 75 plate and sections together, nuts threaded on the inner ends of said screws for holding said screws in place, the tops of the sections adapted to rest upon the lower pins which are placed on the inner edge of the fire- 80 board for holding the guard or fender in position, an adjustable front plate adapted to rest between the upper pins and the upper inner edge of the fire-board and upon the upper edge of the fender, composed of two 85 sections having slots formed therein, joiners, screws passing through said joiners and the slots in the sections, nuts threaded on the inner ends of said screws, a blind secured to the outer faces of the joiners, and a knob 90 attached to said blind.

In testimony whereof, I have hereunto affixed my signature in the presence of two subscribing witnesses.

JOHN M. MASSEY.
